UNITED STATES PATENT OFFICE.

THOMAS A. OLSON, OF HOUSTON, TEXAS.

CLEANING DEVICE.

Application filed February 3, 1928. Serial No. 251,559.

My invention relates to devices for removing and cleaning rust, scale, paint, etc., from metallic surfaces and has for an object to provide an extremely simple and compact structure which may be easily handled and is highly effectual and economical in operation. The scope of my invention is not to be limited to the details as shown but extends to whatever construction may be included within the terms or language of the appended claims.

In the drawings:

Figure 1 is a top plan view partially broken away, of my improved surface cleaning device;

Figures 2 and 2^a illustrate a somewhat diagrammatic showing of the path the cutters assume in cleaning straight and curved surfaces;

Figure 3 is a transverse sectional view taken on the line 3—3 of Figure 1, looking in the direction of the arrows, and

Figure 4 is a similar view illustrating my invention as applied to the outlet end of conventional sheet straightening rollers.

My invention, in the form or embodiment shown in the drawings and briefly described, comprises a hood or casing, indicated generally as at 10, having downwardly curved side portions, 11, and substantially straight end walls 12. Each of the end walls, 12, are provided with a pair of spaced journal bearings, 13, for the purpose of mounting the rotatable shafts, 14.

Members, 15, each preferably having three radially extending arms, are keyed or otherwise secured upon the rotatably mounted shafts, 14, and are so arranged upon their respective shafts that they will not interfere during their rotative movement and at the same time constantly maintain their respective interdental arrangement, which, it will be noted, with reference to Figure 3, is preferably in reverse directions.

Openings, 16, are provided near the outer ends of each of the arms constituting the member, 15, for the purpose of receiving and supporting the rods, 17. These rods, 17, may be held in their proper position within the members, 15, by means of cotter pins, 18, or the like.

A plurality of toothed rollers or cutters, 19, are mounted upon each of the rods, 17, and between each of the oppositely disposed or mating pairs of arms of the member, 15. There is a relatively wide space between each

of the rollers, 19, which will permit them to rotate freely without binding and with the minimum amount of side scraping while in operation.

The rollers, 19, are provided with circular bores, 20, concentric to the periphery thereof and of a diameter substantially twice that of the rods, 17, upon which they are mounted. By reason of the fact that the surface of the bore, 20, of each of the discs or cutters, 19, are relatively smooth, a rolling action between the cutters and their respective rods are obtained with the minimum amount of friction. Although I have disclosed diagonally cut teeth upon the periphery of the cutters or discs, 19, it is to be understood that teeth or projections of varying forms may be provided, depending upon the nature of the surface of the metal to be cleaned or treated.

In Figures 2 and 2^a are illustrated the substantial contour the cutters, 19, would assume in operating against flat and curved surfaces. The dot and dash lines, 21, indicate the path of movement of the rods, 17, whereas the path of movement of the discs or cutters, 19, are represented by the dotted lines, 22. It is, of course, obvious that when the cutter, 19, strikes the surface of the work represented by the line, 23, the cutter will be deflected from its rotary course at the point, a, to a course parallel with the surface to be cleaned, continuing in line therewith up to the substantial point indicated at b. From the point, b, the cutters gradually roll outwardly upon their respective rods, 17, until they are in a substantially horizontal position when they again assume their furthest outward position, as shown by the dotted line, 22. In this manner, it will be readily understood, the surface of the work to be cleaned receives a sharp blow by the entire series or gang of cutters, from which point the gang of cutters roll along the surface for a distance depending upon the height of adjustment between the cutters and the work.

Referring now to Figure 2^a, it will be noted that the dotted line from a' to b', representing the path of movement of that portion of the cutters, is of the same substantial contour as the surface, 23'. This action of the cutters would occur as, for example, when cleaning the outer surface of tanks or other curved surfaces.

For the purpose of predeterminedly ad-

justing the length of the contacting or cutting action between the discs or cutters, 19, and the respective surface to be cleaned, I provide a vertically mounted adjusting screw, 24, in each corner of the hood or casing, 10, which is preferably threaded through respective lugs, 25. Handles, 26, are preferably formed upon the upper surface of the casing, 10, for the purpose of readily moving my improved cleaning device with respect to the work to be cleaned. By placing the motor, M, upon the upper side of the casing, 10, and arranging the driving gears, 27, relatively close to one end thereof, a very compact and self contained cleaning device is obtained.

Referring now to Figure 4, wherein I employ a pair of oppositely disposed cleaning elements, one on either side of the sheet, 28, driving means other than electric motors, may be employed, as, for example, they may be driven from the same power employed in driving the rollers or from any other suitable source. In this instance, each of the hoods or casings, 10, may be moved to and from the sheet, 28, by means of the bolts, 29, which are carried by the horizontal beams, 30, and the slots, 31, which are formed through the casing, 10. It will be readily seen that in this application of my invention, the scale or paint from both sides of the sheet, 28, would be simultaneously cleaned in one operation.

Although I am aware of the fact that numerous attempts have been made to accomplish this result in various ways, yet I know of no device which is so constructed as to so effectually clean metallic surfaces of rust, paint, or scale, by exerting a rolling action with considerable pressure against the surface, and uniformly parallel with respect thereto.

It will also be obvious from the disclosures that the paths of movement of both sets of disks cross one another during their rotative movement. This is due to the tim-

ing of one of the sets of arms with respect to the opposite set of disk-carrying arms. By this arrangement the oppositely rotating arms may be disposed relatively close to one another to attain the compactness essential to a device of this nature.

I claim:

1. A cleaning device for metallic surfaces comprising a casing, a plurality of pairs of 55 rotatably mounted members, each having a series of rods carried thereby and extending in parallel, a plurality of discs having roughened outer surfaces mounted upon said rods and loosely spaced with respect thereto, 60 each of said discs having a relatively large circular opening concentric with respect thereto, a plurality of members arranged to bear against the metal to be cleaned for maintaining a substantially uniform distance 65 between the case and said metal and driving means for rotating said members in opposite directions.

2. A cleaning device for metallic surfaces, comprising a casing, a plurality of parallel 70 shafts rotatably mounted within the casing, a pair of oppositely disposed members keyed to each of said shafts and each of the members having outwardly extending arm portions, rods mounted near the outer ends of 75 each of said arms, a plurality of discs having roughened outer surfaces mounted upon the rods and loosely spaced with respect thereto, each of said discs having an opening substantially twice the diameter of the respective rods, for permitting the discs to roll with respect thereto, said rods being so arranged that the path described by the rotation of one of the sets of discs extends beyond that described by the other set of discs, 80 a plurality of spacing members carried by the casing for varying the duration of contact of the cutters against said metal surface to be cleaned, and means for rotating said shafts in opposite directions.

T. A. OLSON.
